UNITED STATES PATENT OFFICE.

BROR A. ADLER, OF CHICAGO, ILLINOIS, ASSIGNOR OF ONE-HALF TO PETER A. LORENZ,
OF CHICAGO, ILLINOIS.

HOROLOGICAL MOTOR.

1,144,748.

Specification of Letters Patent. Patented June 29, 1915.

Application filed June 23, 1913. Serial No. 775,215.

To all whom it may concern:

Be it known that I, BROR A. ADLER, a subject of the King of Sweden, residing at Chicago, in the county of Cook and State of Illinois, have invented certain new and useful Improvements in Horological Motors, of which the following is a specification.

My invention relates broadly to means for producing intermittent motion.

10 It is especially adapted as a horological motor as in use for secondary clocks, operated in response to a master clock, wherein pneumatic, electric or other suitable power-transmitting means communicates periodic impulses to the motor mechanism to move the time-indicating hands of the secondary clock in harmony with the movement of similar hands of the master clock.

One of the objects of my invention is to 20 provide a simple, reliable, cheap of construction, and efficient motor.

Another object of my invention is to provide, in a motor of the class described, means for periodically correcting the variations 25 from the master clock, that may occur in the secondary clock within a given period, so as to secure exact and positive concurrence of the positions of the time-indicating hands of the secondary clock with those of the master 30 clock.

Other and further objects of my invention will become readily apparent to persons skilled in the art from a consideration of the following description when taken in conjunction with the drawings, wherein—

Figure 1 is a front view of the secondary clock mechanism that is responsive to the master clock and adapted to move the hands of the secondary clock coincidentally with 40 those of the primary or master clock; Fig. 2 is a side elevation of the device; Fig. 3 is a plan view of the motor mechanism; Fig. 4 is a front view with a part of the mechanism removed to show more clearly the time-correcting mechanism; Fig. 5 is an enlarged 45 vertical section taken on line 5—5 of Fig. 1; Fig. 6 is a rear view of an eccentric mechanism adapted for lifting the pawls when it is desirable to move the hands of the secondary clock by manual means to "set" the clock; Fig. 7 is the circuit closing mechanism used on the master clock; and Fig. 8 is an enlarged broken-away view of the pawls.

In all the views the same reference characters indicate similar parts.

10 is the plate upon which the mechanism is mounted having perforations 11 through which screws pass in order to secure it to the dial 12, the outlines of which are shown in dotted lines in Fig. 1. The plate is spaced 60 apart from the dial and is so held by separating sleeves 13. Minute-hand and hour-hand arbors 14 and 15 pass through the dial plate and through the frame plate 10 and have connections with the minute-hand 16 65 and the hour-hand 17, respectively. Secured to the minute arbor 14 is an hour wheel 18 provided with 60 teeth adapted to move the minute-hand one minute at each impulse. The train of gears to connect the minute 70 arbor and the hour arbor, as usual, is provided in the gear wheels 19—20 and the intermeshing pinions 21 and 22. This train of gears is common in all clocks and especially in secondary electrical clocks and 75 needs no further explanation.

The teeth 23 of the ratchet wheel 18 are each provided with fore-and-aft radial surfaces and inclined or tangential end surfaces. A locking pawl 24 is pivoted as at 25 and 80 is further provided with a laterally projecting part 26 that is adapted for engagement in the interdental space between the radial surfaces of adjacent teeth to lock the wheel against movement in either direction. It is 85 also provided with an inclined tapered projection 27 extending laterally from the main body of the pawl toward the impulse pawl for coöperation with a similar projection from the impulse pawl. 28 is the impulse 90 pawl provided with a similar lateral projection 29 for engagement of the projection 27 on the locking pawl. The impulse pawl is also provided with a projection 30 for engagement with the teeth 23 of the ratchet 95 or hour wheel. The part 30 in normal position is removed or drawn back somewhat from the teeth of the wheel which it is ultimately intended to engage and the pawl-lifting part 29, in normal position, is practically in contact with the coacting part 27 of the locking pawl. When the impulse pawl is urged forward, on its power stroke, the parts 27 and 29 engage and thereby the locking pawl is lifted from engagement with the teeth before the part 30 engages the teeth to move the wheel. When the part 30 has moved the minute hand and wheel a distance equal to the distance between adjacent teeth, the projection 29 of the impulse pawl will 100

105

110

have passed by the projection 27 on the locking pawl and on the return excursion of the impulse pawl the part 29 will ride over and pass above the part 27 of the locking pawl, thereby forcibly thrusting the locking pawl into interdental position between adjacent teeth of the wheel 18 to lock it. It is therefore clear that the initial movement of the impulse pawl serves first to raise the locking pawl before the wheel 18 is moved by engagement of the part 30 of the impulse pawl with any one of the teeth of the wheel.

The impulse pawl is pivoted, as at 31, to a vertical arm 32 which normally rests against the stop 33. An armature 34 is pivoted to a shaft 35 which is connected to the vertical arm 32. A spring 36 serves to hold the armature 34 and the vertical arm 32 yieldingly in the retracted position shown in Fig. 1. An electromagnet 37, in conjunction with the armature 34, is the electro-responsive device which, when energized, serves to move both of the pawls when power is applied to the wheel 18. An electromagnet 38 is provided with a responsive armature 39 which has an extended arm 40, normally resting upon one side of the armature 34 and being yieldingly held by means of the spring 41.

When the electromagnet 37 is energized the armature 34 is attracted moving the vertical arm 32 to the left and thereby giving the power impulse to the impulse pawl 28. It will be observed that the first or initial movement of the impulse pawl will serve to raise the locking pawl from its locked position by engagement of projection 29 of the impulse pawl, co-operating with a similar projection 27 of the locking pawl, which operation will serve to raise the locking pawl free from the teeth of the ratchet wheel and subsequently the projection 30 of the impulse pawl, will move the wheel while it is so free during a further movement of said impulse pawl. About the time the wheel has moved to the extent of the distance between two adjacent teeth, the projection 29 of the impulse pawl will have passed the projection 27 of the locking pawl and the return stroke of the impulse pawl will tend to press the locking pawl back into its former position as the part 29 rides over the part 27 in the return stroke of the impulse pawl. A spring 42 controls the impulse pawl and a similar spring 43 controls the locking pawl, but both springs act upon the locking pawl at the time the projection from the impulse pawl is riding over the similar projection on the locking pawl, and therefore the locking pawl is assured of being returned promptly to its locking position.

In Fig. 1, the circuit for connecting the said electro-responsive means, and a master clock for controlling said circuit, are diagrammatically shown, wherein 45 is a cam

wheel adapted to be rotated in the direction shown by the arrow on an arbor which completes a revolution once every minute. It is provided with a notch 46, into which the roller 47, secured to an elastic spring 48, will drop when the wheel is rotated until they are coincident, as when it is rotated slightly more than that shown in the drawings. When the roller 47 drops into the notch 46 circuit will be closed between the spring 48 and the contact 49, and the electromagnet 37 will be energized through the following circuit: from battery B over the wire 50, through spring 48 to contact 49, over wires 52 and 53 to the electromagnet 37, 75 and thence over wires 54 to 57 inclusive, to the contact 58, over the flexible spring 59 to the extension 60 on the armature 34, and back to battery over the wire 61. When the armature 34 is attracted by the magnet 37 contact is thus broken between the spring 59 and the armature extension 60, thus breaking the circuit of the energized magnet and establishing circuit for the unlocking magnet. 90

During the rotation of the minute commutating cam or wheel 45 the contact wheel 47 will have arisen from the notch 46 and the wheel 51' will have dropped into the notch. At this time the raising of the wheel 47 will open circuit between the spring 48 and the contact 49, and the dropping of the wheel 51' into the notch 46 will establish circuit between the spring 51 and the contact 64, and the circuit will then be completed as follows: from the battery B over the wire 50 to the spring contact 51, to the contact 64 and over the wires 65, 66, and 67 to the electromagnet 38. Parenthetically it may be stated that when the armature 34 100 of the electromagnet 37 is attracted, the extension 40 of the unlocking electromagnet 38 will drop behind armature 34 and retain or lock it in the position in which it has been placed by the electromagnet 37. Now when 105 the armature 38 is attracted by the current flowing over the circuit just described, the armature 39 will be drawn toward the unlocking electromagnet 38, and the projection 40 will be lifted, allowing the armature 34 110 of the electromagnet 37 to be returned to its normal position by means of the spring 36. However the circuit is completed from the electromagnet 38 over the wires 68, 69, and 70 to the contact 71 and over the elastic spring 63. The armature 34, is now locked in depressed position by extension 40 which moved in over the armature when electromagnet 37 was energized as above shown, so that extension 60 is in contact with the 115 spring 63, and therefore the circuit will be completed from the spring 63 with the extension 60 and to the frame of the device over the wire 61 back to battery, completing the circuit through the releasing or unlock 120

125 130

ing electromagnet 38 and permitting the armature 34 to return to its normal position at the same time the pawl 28 has been returned to its normal position and the hands have been moved the distance of one minute.

It is desirable to correct any irregularity that may exist in the position of the time-indicating hands on the secondary clock with reference to the position of similar hands on the primary or master clock, and it is further desirable that such correction shall be made positively, preferably once every hour, and to this end I provide mechanism for this purpose consisting of levers 72 and 73, pivoted as at 74 and 75, respectively, to a stationary part of the frame. The levers are yieldingly held in extended or open position by means of the spring 76. A projection 77 on lever 72 extends into a recess 78 on lever 73 so that when lever 72 is brought up to a substantially vertical position this connecting means will operate to bring lever 73 also into a vertical position parallel with the companion lever, as shown in Fig. 4. Each of the levers are provided with laterally extending parts 80 and 81 respectively, for engagement with a screw or projection 79 when the said levers are in or are approaching substantially vertical positions. Secured to the lever 72 is an armature 83, which is responsive to the electromagnet 84, to move the said levers to the vertical positions shown in Fig. 4 when the said magnet is energized. When the levers are in open or extended position, substantially as shown in Fig. 1, the parts 80 and 81, which laterally extend toward the hour wheel 18 from the said levers, are removed from the path of the screw or projection 79 which is secured to the wheel.

The master clock 85 is provided with a contact 86, preferably located adjacent the point indicated by the numeral 12, which is adapted for connection with the minute hand 87 of the master clock. When the minute hand 87 is in contact with the point 86, electric circuit is completed over the following conductors: Starting from the positive side of battery B, over the wire 50', through the spring 51, and after the wheel 51' of the spring 51 has passed into the notch 46 of the wheel 45, circuit will be completed from the spring 51 to the contact 64, through the wires 65, 66, and 67, thence through the release magnet 38 over the wires 68, 69, the wire 88, through electromagnet 84, and over the wire 89, back to the contact 86 of the master clock, through the minute hand 87, over the wire 62 to wire 61, and back to the battery; thus completing the electric circuit and energizing the release magnet 38 and the electromagnet 84, causing the levers 72 and 73 to be drawn into substantially a vertical position shown in Fig. 4, and thereby moving the hour wheel by contact of either

lever with the projection 79 to move it into a substantially vertical position, thereby correcting all inequalities that may exist with reference to the relative positions of the hands on the secondary clock and that of the hands on the primary clock. It is evident, however, that the hour wheel 18 cannot be moved so long as the locking pawl 24 is in contact between the teeth of the hour wheel 18, and to this end I provide on the lever 72 a tapered arm 90, pivoted as at 91, and elastically held in the position shown by spring 92. When the arm 72 is drawn up to the position shown in Fig. 4, the tapered end of the arm 90 passes under the projection 93 on the locking pawl 24 and under a similar projection 94 under the impulse pawl 28, thus lifting the said pawls and permitting the wheel 18 to be turned or rotated. Each time the minute hand 81 passes contact 86 (that is, at each hour) the projection 79 should be in precisely vertical position, but should the secondary clock have run slower or faster than it should, then the projection 79 will be either on the right or the left hand side of the vertical line taken through the axis of the wheel 18, indicating that the secondary clock is either too fast or too slow, and when the levers 72 and 73 are brought up to vertical position, the projection 80 or 81 on the respective levers, either one or the other depending whether the clock is slow or fast, will engage the projection 79 and rotate the hour wheel 18 forwardly or backwardly, as the case may be, sufficiently to bring the projection 79 and with it the hands 16, 17 into the true vertical position, and thus set the hands of the clock back or ahead as circumstances will warrant, thereby correcting the clock periodically to correspond precisely with the conditions existing on the master or primary clock. This correcting circuit is to be closed only for a very short period of time, or during the time that the contact wheel 51 is within the notch 46 of the minute wheel 45, but for a sufficient time to perform the function described. The battery being closed for such short duration, the efficiency of the device will be understood.

As soon as the lever 72 has arrived at its vertical position the interdental portion 26 of the locking pawl 24 will immediately drop back into its locking position between two adjacent teeth of the hour wheel 18, and the projecting arm 90 from lever 72 will ride over the projection 93 on the locking pawl on its return to the normal position shown in Fig. 1, thereby preventing the possibility of moving the hour wheel 18 from the position in which it has been placed by the coöperation of the levers 72 and 73 with the projection 79.

Should it be required at any time that the secondary clock should be "set" by hand,

I provide a manually operable means for lifting the pawls from the hour wheel 18 so that the hands of the clock, together with the hour wheel, may be freely rotated. To this end, I provide a stem 97 which takes through the frame plate 10 and the dial plate 12 of the clock, having an integral disk part 98 projecting from its inner end. The stud or stem 97 passes through the plate 10 and the dial 12, and is adapted to be rotated from the dial side by means of the screw 99. Secured to the disk 98 by means of screw 101 is a stirrup or link 100. It is slotted at its lower end and is guided by a screw 102 which takes into the slot. Near its mid-portion it is provided with a perforation 103, within which are included the lateral projections 27 and 29 of the pawls 24 and 28, respectively, so that when the link 101 is lifted the pawls 24 and 28 are lifted by contact with these projections. A friction washer 105 permits the mechanism, just described, to remain in the position in which it has been moved and therefore the hour wheel 18 will be free to be moved by turning of the minute hand until the parts have been returned to their normal positions shown in Figs. 1, 4, and 8.

It will be observed from the foregoing description that the circuit through the magnets 34, 38, and 84 are closed for a very short period of time. The circuit through the impulse magnet 37 is closed only long enough to operate the pawls and to accomplish the desired power stroke of the impulse pawl, after which the parts so moved by the impulse magnet are locked and held locked, to be subsequently unlocked by the unlocking magnet 38. The circuit necessary to energize the unlocking magnet 38 remains closed only for a fractional part of a second, or until the wheel 51' can drop into the notch 46 after wheel 47 has been lifted from the said notch, and once every hour the electromagnet 84 is energized and

remains energized for a very short period of time, or during the interval that wheels 47 and 51 are passing into and through the notch 46, as heretofore described.

While I have herein described a single embodiment of my invention for the purpose of clear disclosure, it is evident that many changes may be made in the specific structure shown without departing from the spirit and scope of my invention as defined by the appended claims.

What I claim is:

1. In a device of the character described, a ratchet wheel; a locking pawl normally engaging said wheel to lock it against movement in either direction; an impulse pawl, to move the wheel a distance equal to the distance between two adjacent teeth; an electro-responsive means for moving both pawls; a latch for locking said pawl moving means after the said pawls have been so moved and an electro-responsive means for releasing said latch.

2. In a device of the character described, a ratchet wheel; a locking pawl; a pawl for moving said wheel a distance equal to that between two adjacent teeth on the said wheel; electro-responsive means for moving both pawls; an electro-responsive means for locking the pawls in moved position; and means, operable by the pawl-moving means, for opening its own circuit.

3. In a device of the character described, a ratchet wheel; a locking pawl; a pawl for moving said wheel a predetermined distance; electro-responsive means for moving both pawls; and an electro-responsive means for locking the pawls in moved position.

In testimony whereof I hereunto set my hand in the presence of two witnesses.

BROR A. ADLER.

In the presence of—

MARY F. ALLEN,
W. LINN ALLEN.
